UNITED STATES PATENT OFFICE.

ALFRED D. McWHORTER, OF ATLANTA, GEORGIA.

VALVE.

No. 856,899.

Specification of Letters Patent.

Patented June 11, 1907.

Application filed February 7, 1907. Serial No. 356,235.

To all whom it may concern:

Be it known that I, ALFRED D. McWHORTER, a citizen of the United States, residing at Atlanta, in the county of Fulton and State of Georgia, have invented certain new and useful Improvements in Valves; and I do hereby declare the following to be a full, clear, and exact description of the invention, such as will enable others skilled in the art to which it appertains to make and use the same.

This invention relates to improvements in valves for use in connection with train pipe systems and while in the following description and in the drawings forming a part of this application, the valve is disclosed as being automatically operated, still it will be understood that in the broad application of the invention, it is not absolutely necessary that the valve be so automatically operated, but the invention may be carried out for instance in connection with an engineer's valve, such as illustrated in my former patent, No. 784,417, dated March 7, 1905.

Broadly, the invention consists of a valve adapted to be associated with a train pipe system having main and auxiliary reservoirs, the ports in said valve being so positioned with relation to the train line and said auxiliary reservoir and the braking cylinder, that in applying the brakes, the compressed air is initially conducted to the braking cylinder from the supplementary reservoir and subsequently is directly conducted to the braking cylinder from the train line pipe. Also also upon the release of the brakes, the back pressure from the braking cylinder is first conducted to the auxiliary reservoir and there stored and subsequently, during a further movement of the valve, the air in the braking cylinder is discharged to atmosphere.

It will be understood that the invention is not limited to the exact details illustrated and described in the present application, but for the purposes of disclosure, reference is had to the accompanying drawings illustrating practical embodiments of the invention, in which like letters designate the same parts in the several views, and in which:—

Figure 1 is a diagrammatic plan view showing the association of the automatic valve with a train pipe system. Fig. 2 is a horizontal section through the valve casing, and showing the valve in its normal position with the brake cylinder in communication with the atmosphere. Fig. 3 is a similar

view showing the valve in a different position, with the auxiliary reservoir and brake cylinder in communication. Fig. 4 is a similar view showing another position of the valve just prior to opening communication between the train line pipe and the brake cylinder. Fig. 5 is a similar view, showing the position of the valve after it has passed to its extreme position and with the inlet port open so that the train line pipe and brake cylinder are in communication. Fig. 6 is a cross section on the line 6--6 of Fig. 2. Fig. 7 is a view showing a modified form of valve and in diagrammatic plan its association with a train pipe system and its accessories. Fig. 8 is a longitudinal sectional view through said modified form of valve, and Figs. 9 and 10 are fragmentary views, showing different positions of the valve.

1 designates a casing having the heads 2 and 3, one end of the casing being enlarged as at 4 and suitable packing material 5 being disposed between the heads and the casing and its lining.

6 designates a brass liner within the enlarged chamber 4 of the casing and 7 is a similar brass liner in the reduced or valve chamber 8.

The head 3 of the casing is apertured as at 9 to receive a branch pipe 10 from the main train pipe 11.

12 is an inlet port or by-pass V-shaped in order to make it possible to graduate the application of the pressure to the braking cylinder when uncovered by the piston hereinafter described. The liner 7 is also provided with a plurality of ports 13, 14, and 15 communicating with ports formed in the main casing 1 and leading respectively to the brake cylinder, the atmosphere and the auxiliary reservoir.

16 designates a plunger rod operating within the valve chamber 8 and provided at one end with the piston 17 having suitable packing rings and operating in the enlarged or piston chamber 4. The other end of the plunger rod 16 is hollow as at 18 and threaded to receive an apertured retaining cap 19 through which passes a headed pin 19 disposed in the hollow portion 17, and the headed portion of said pin being in engagement with a coil spring 20 located within said hollow portion. The lower portion of said rod is recessed as at 21 to receive the sliding valve 22, which operates within the seat 23 formed in the liner 7, the upper portion of said rod

carrying a guide 16^a which fits and slidely engages the liner 7 for guiding the inner end of the rod 16. This valve may be held firmly seated to prevent leakage by any suitable means, and in the drawings this is simply illustrated (Fig. 6) as comprising a screw or headed pin 24 secured to the valve and passing upwardly into recesses 25 in the plunger rod, a coil spring encircling the end of said screw or pin within said recesses and tending to force said valve from said plunger rod.

Referring to the construction shown in Figs. 7 to 10, the arrangement of the ports in the valve casing is slightly changed, and the construction of the valve itself modified. It will be seen that in this construction the inlet port 12 has been dispensed with in the piston chamber, the corresponding port 12^a leading to the main reservoir being located adjacent the sliding valve 21^a. This valve is of a slightly modified construction, as shown, for the particular arrangement of ports, and consists of the sliding member having two passage-ways 21^b and 21^c formed therein. In this construction, as in that previously described, the plunger rod is bored to receive a coil spring operating on a headed pin for a purpose hereinafter appearing.

From the foregoing, and referring to Figs. 1 to 6, the valve being in the off position shown in Fig. 2, it will be seen that upon operating the engineer's valve indicated at 26 to allow of an increased pressure in the train pipe 11, this pressure passing through the branch pipe 10 in front of the piston 17 will force the piston rearwardly against the lesser pressure from the auxiliary reservoir until the piston and the valve moved thereby assume the position shown in Fig. 3 when communication is open between the auxiliary reservoir and the brake cylinder and thus the brakes are initially operated through the medium of the air stored in the auxiliary reservoir. It will be observed that the passage of the valve from the position shown in Fig. 2 to Fig. 3 will be gradual owing to the cushioning effect of the compressed air from the auxiliary reservoir behind the piston. Upon continued movement of the valve to the position shown in Fig. 4, the port to the auxiliary reservoir is closed and communication is being opened between the main reservoir through the train line pipe 11, branch pipe 10, piston chamber 4, inlet port 12 and brake cylinder port 13. In this position of the valve, it will also be seen that the headed pin 19 is just engaging the head 21. As the piston and plunger are forced rearwardly to complete the opening of the port 12, as shown in Fig. 5, the headed pin has been forced inwardly within the recesses 17 against the tension of the spring 20. In this position full pressure from the main reservoir is conducted to the brake cylinder and the instant that full pressure is

established, the pressure in the brake cylinder equalizing the pressure in the train pipe, the spring 20 will force the piston 17 to the position shown in Fig. 4. Upon the release, when the engineer's valve is operated, the back wave or pressure from the brake cylinder being greater than the reduced pressure in the train pipe, the piston and valve will be slowly pushed forward, first opening communication (Fig. 3) between the brake cylinder and auxiliary reservoir, this communication being maintained open until equalization takes place between the pressures in the brake cylinder and auxiliary reservoir, when the valve will have been moved to the off position shown in Fig. 2, with the brake cylinder in communication with atmosphere.

In the construction shown in Figs. 7 to 10, it will be observed that the port 12^a in the valve casing is dispensed with and a direct connection with the casing adjacent the valve is made through the port 12^a with the main reservoir. The main reservoir is also connected up directly with the auxiliary reservoir, a reducing valve 27 being interposed therebetween. I have also shown (Fig. 9) a spring 28 for holding rod and valve in position. In this construction instead of having to apply the brake several times in the mornings to store up the auxiliary reservoir, by the arrangement just stated, the auxiliary reservoir may be stored up directly from the main reservoir so that it is all ready for co-operating with the valve when the train is first started up. In the off position shown in Fig. 8, upon operating the engineer's valve, pressure is introduced in front of the piston 17, the operation then being substantially as heretofore described with reference to Figs. 1 to 4, and the several positions of the valve being illustrated by Figs. 8 to 10.

From the foregoing description, it will be observed that one of the great advantages of this invention is that when several cars are coupled and the valve corresponding to the engineer's valve on each car being open to form an open conduit through the train pipe, the automatic control of the main reservoirs carried by each car is attained at the cab of the train so that the contents of the main reservoir of each car is brought into use and not simply the main reservoir on the first car; and this is done without any check valves in the train line pipe, but simply by the automatically operating valve 1.

Having thus described the invention, what I claim is:

1. In a train pipe system embracing a main reservoir, an auxiliary reservoir and a brake cylinder, means for controlling the flow of compressed air therethrough, comprising a valve operative to initially open communication between said auxiliary reservoir and brake cylinder, thence between said main reservoir and said brake cylinder and upon

release to initially open communication between said brake cylinder and auxiliary reservoir and thence between said brake cylinder and atmosphere, substantially as described.

5. 2. A valve casing provided with inlet, atmosphere, brake cylinder and auxiliary reservoir ports, and valve mechanism therefor operating to bring said ports into communication in the following sequence:—auxiliary reservoir and brake cylinder, inlet and brake cylinder; and on release brake cylinder and auxiliary reservoir and brake cylinder and atmosphere, substantially as described.

15. 3. In a train pipe system, the combination with a main reservoir, a brake cylinder and an auxiliary reservoir, of valve mechanism operating upon increased pressure in the train line pipe to open communication initially between said auxiliary reservoir and 20 brake cylinder, thence between said main reservoir and brake cylinder, and upon reduced pressure in the train line pipe to initially open communication between said brake cylinder and auxiliary reservoir and 25 thence between said brake cylinder and atmosphere, substantially as described.

4. In a train pipe system, the combination with a valve casing having inlet, atmosphere, brake cylinder and auxiliary reservoir ports, 30 of mechanism for opening communication between said ports *seriatim*, substantially as described, comprising a plunger rod mounted in said casing, bored at one end and provided with a piston head at the other end, a coil 35 spring mounted in said bore, a headed pin disposed within said bore and in engagement with said spring, an apertured retaining cap for closing said bore and forming a bearing for the shank of said headed pin, and a valve 40 operated by said plunger, substantially as described.

5. An automatically operating valve for train pipe systems, comprising a casing having an enlarged and a reduced chamber, ports substantially as described being disposed in said 45 reduced chamber, a plunger rod and valve

operating in said reduced chamber and having a piston head operating in said enlarged chamber, said enlarged chamber being in communication with the train line pipe, substantially as described.

6. In a train pipe system, the combination with the train pipe, main reservoir, auxiliary reservoir and braking cylinder, of automatically operating valve mechanism for the purpose substantially as described, comprising a 55 valve casing having an enlarged and a reduced chamber, brake cylinder, auxiliary reservoir, and atmosphere ports being disposed in said reduced chamber, and said 60 train pipe communicating with said enlarged chamber, a piston operating in said enlarged chamber and provided with a rod extending within said reduced chamber, and a valve 65 operated by said rod controlling said ports in said reduced chamber, substantially as described.

7. In a train pipe system, the combination with the train pipe, main reservoir, auxiliary reservoir and braking cylinder, of automatically operating valve mechanism for the purpose substantially as described, comprising a 70 valve casing having an enlarged and a reduced chamber, brake cylinder, auxiliary reservoir, and atmosphere ports being disposed 75 in said reduced chamber, and an inlet port disposed in said enlarged chamber, said enlarged chamber being in communication with the train line pipe, a piston operating in said enlarged chamber and provided with a 80 rod operating in said reduced chamber, and a valve operated by said rod, said valve controlling said brake cylinder, atmosphere and auxiliary reservoir ports, and said piston controlling said inlet port, substantially as described.

In testimony whereof, I affix my signature, in presence of two witnesses.

ALFRED D. McWORTER.
